UNITED STATES PATENT OFFICE

WILLIAM H. BANZETT, OF BERGENFIELD, NEW JERSEY, ASSIGNOR TO AMERICAN LITHOGRAPHIC COMPANY, INC., OF NEW YORK, N. Y., A CORPORATION OF NEW YORK

PLATE-REGISTERING MEANS

Application filed February 2, 1929. Serial No. 337,044.

This invention relates to plate registering means and has for its object to bring a printing plate, on a cylinder or elsewhere, into correct register widthwise with the material 5 on which the printing is to be done. After one set of impressions has been made from one of a plurality of plates prepared in corresponding registry, as a set of multi-color plates for instance, it is often found 10 that the paper on which the printing is done has stretched transversely, from atmospheric conditions or otherwise, so that when one portion of a plate from which a second color, for instance, is to be printed, is in correct 15 registry with the previously printed color, another portion is found to be slightly out of register. For instance, while the midportion of the plate could be brought into registry with the midportion of the first printed 20 color, the edge portions would be found short of registry because of the stretching of the paper.

While this lack of registry may be not more than the width of a line, it is often sufficient, 25 in fine work, to seriously injure the desired result. The object of the present invention is to provide means for correcting this lack of registry.

To that end my improvements comprise 30 features illustrated in their present preferred embodiment in the drawing accompanying this specification, wherein Figure 1 is an end elevation of a portion of a printing cylinder. Fig. 2 is a plan view corresponding therewith. Fig. 3 is a fragmentary plan view of 35 a detail of the device showing the plate flat, in one plane.

My improvements comprise providing the printing plate 2 which is wrapped about the 40 cylinder bed 20 or laid flat as in Fig. 3, with one or more inwardly reaching slits, as 3, from one or both edges thereof and located at convenient distances from said edges of the plate. Preferably two such slits are cut 45 in the plate at about one quarter of the width of the plate from each edge. That leaves the midportion half 2^a of the plate separated at its end portion from the adjoining opposite quarter portions 2^b and 2^c. Said midportion 50 may be secured to the cylinder by means of

the usual pivoted tension clamps 4, 5 which lie between trunnion blocks 6, 7, 8 respectively. Said clamps fill the spaces between their respective opposite blocks so they have no movement transverse the cylinder. 55

Plate portions 2^b and 2^c are also secured by similar clamps 9, 10 which are pivotally mounted on short shafts 11, 12 in trunnion blocks 13, 6 and 8, 14 respectively. Said shafts are prevented endwise movement by pins, as pin 15 fastening shaft 11 in block 6. Also clamps 9, 10 are provided with means, as set screw 16 to clamp 9 for securing said clamps against endwise movement on their respective shafts, after said clamps have been 60 adjusted to desired positions. To facilitate the movement of clamps 9, 10 measured distances for adjustment, stop screws 17, 18 are 65 provided.

The operation of my improvements is as 70 follows: The midportion of the sheet to receive its second or later printing is brought into transverse register with the midportion 2^a of plate 2 by known means. Then, if the paper is found to have stretched transversely since the previous impression, set screw 17 is backed off a distance equal to the desired 75 correction for plate portion 2^b and clamp 9 is moved to the left, Fig. 2, by hand or by some convenient means such as a pinch bar, until it contacts with the point of stop screw 17, when clamp screw 16 is set against shaft 11 thereby securing clamp 9 and the end of plate portion 2^b in its grasp, in their new 80 positions in which plate portion 2^b registers with the paper from which it is to be printed. The other edge portion 2^c of the plate may be similarly adjusted to the right. If necessary or desirable, the tension bolts for clamps 9 and 10, as bolt 19 of clamp 9, may be loosened during the operation of shifting said clamps so that they will have more freedom of movement. After said clamps have been 85 shifted said bolts may be tightened to stretch the edge portions of the plate on the bed or cylinder. 90

I claim:

1. That improvement in plate registering means including in combination a bed, a printing plate thereon, means for securing 100

one end of the plate to the bed, a plurality of clamps mounted and adapted for engaging and stretching the other end of the plate on said bed, one of said clamps being constrained 5 against transverse movement, another of said clamps being mounted for transverse movement and a slit in said plate extending inwardly of said plate away from its transverse edge, said slit being located between 10 said clamps, whereby, by moving the transversely movable clamp away from the first mentioned clamp, those portions of said plate on either side of said slit are separated.

2. That improvements in plate registering means including in combination, a bed, a printing plate thereon, means for securing one one of the plate to the bed, a plurality of clamps mounted and adapted for engaging and stretching the other end of the plate on 20 said bed, one of said clamps being constrained against transverse movement, another of said clamps being mounted for transverse movement, a slit in said plate extending inwardly of said plate away from its transverse edge, 25 said slit being located between said clamps, whereby, by moving the transversely movable clamp away from the first mentioned clamp, those portions of said plate on either side of said slit are separated and means for securing 30 said transversely movable clamp in its adjusted position.

3. That improvement in plate registering means including in combination, a bed, a printing plate thereon, means for securing one 35 end of the plate to the bed, a plurality of clamps mounted and adapted for engaging and stretching the other end of the plate on said bed, one of said clamps being constrained against transverse movement, another of said 40 clamps being mounted for transverse movement, a slit in said plate extending inwardly of said plate away from its transverse edge, said slit being located between said clamps, whereby, by moving the transversely movable 45 clamp away from the first mentioned clamp, those portions of said plate on either side of said slit are separated, means for securing said transversely movable clamp in its adjusted position and a stop screw adapted to be 50 engaged by said transversely movable clamp for adjustably limiting its transverse movement.

4. That improvement in plate registering means including in combination, a bed, a printing plate thereon, means for securing one 55 end of the plate to the bed, a plurality of clamps mounted and adapted for engaging and stretching the other end of the plate on said bed, one of said clamps being constrained 60 against transverse movement, a clamp on either side of said transversely fixed clamp, said clamps on either side being mounted for transverse movement and two slits in said plate extending inwardly of said plate away 65 from its transverse edge, said slits being lo-

cated between said transversely fixed clamp and each of said transversely movable clamps, whereby, by moving the transversely movable clamps away from the first mentioned clamp, those portions of said plate engaged by said transversely movable clamps are moved from the midportion of the plate engaged by said first mentioned clamp. 70

5. That improvement in plate registering means including in combination, a bed, a printing plate thereon, means for securing one end of the plate to the bed, a plurality of clamps mounted and adapted for engaging and stretching the other end of the plate on said bed, one of said clamps being constrained 75 against transverse movement, a clamp on either side of said transversely fixed clamp, said clamps on either side being mounted for transverse movement, two slits in said plate extending inwardly of said plate away from its transverse edge, said slits being located between said transversely fixed clamp and each of said transversely movable clamps, whereby, by moving the transversely movable clamps away from the first mentioned clamp, those portions of said plate engaged by said transversely movable clamps are moved from the midportion of the plate engaged by said first mentioned clamp, and means for securing said 80 transversely movable clamps in their adjusted positions. 85

6. That improvement in plate registering means including in combination, a bed, a printing plate thereon, means for securing one end of the plate to the bed, a plurality of clamps mounted and adapted for engaging and stretching the other end of the plate on said bed, one of said clamps being constrained 90 against transverse movement, a clamp on either side of said transversely fixed clamp, said clamp on either side being mounted for transverse movement, two slits in said plate extending inwardly of said plate away from its transverse edge, said slits being located between said transversely fixed clamp and each of said transversely movable clamps, whereby, by moving the transversely movable clamps away from the first mentioned clamp, those portions of said plate engaged by said transversely movable clamps are moved from the midportion of the plate engaged by said first mentioned clamp, and means for securing said 95 transversely movable clamps in their adjusted positions. 100

105

7. That improvement in plate registering means including in combination, a bed, a printing plate thereon, means for securing one end of the plate to the bed, a plurality of clamps mounted and adapted for engaging and stretching the other end of the plate on said bed, one of said clamps being constrained against transverse movement, a clamp on either side of said transversely fixed clamp, said clamp on either side being mounted for transverse movement, two slits in said plate extending inwardly of said plate away from its transverse edge, said slits being located between said transversely fixed clamp and each of said transversely movable clamps, whereby, by moving the transversely movable clamps away from the first mentioned clamp, those portions of said plate engaged by said transversely movable clamps are moved from the midportion of the plate engaged by said first mentioned clamp, and means for securing said transversely movable clamps in their adjusted positions. 110

115

8. That improvement in plate registering means including in combination, a bed, a printing plate thereon, means for securing one end of the plate to the bed, a plurality of clamps mounted and adapted for engaging and stretching the other end of the plate on said bed, one of said clamps being constrained against transverse movement, a clamp on either side of said transversely fixed clamp, said clamp on either side being mounted for transverse movement, two slits in said plate extending inwardly of said plate away from its transverse edge, said slits being located between said transversely fixed clamp and each of said transversely movable clamps, whereby, by moving the transversely movable clamps away from the first mentioned clamp, those portions of said plate engaged by said transversely movable clamps are moved from the midportion of the plate engaged by said first mentioned clamp, and means for securing said transversely movable clamps in their adjusted positions. 120

125

In witness whereof, I hereby affix my signature this 28th day of January, 1929.

WILLIAM H. BANZETT.
